[57] CLAIM

The ornamental design for a connector unit, as shown and described.

DESCRIPTION

FIG. 1 is a right side elevational view of a connector unit showing my new design; the left side elevational view being a mirror image thereof;
FIG. 2 is a top plan view thereof;
FIG. 3 is a bottom plan view thereof;
FIG. 4 is a front elevational view thereof;
FIG. 5 is a rear elevational view thereof;
FIG. 6 is a top front perspective view thereof;
FIG. 7 is a right side elevational view of a second embodiment; the left side elevational view being a mirror image thereof;
FIG. 8 is a top plan view thereof;
FIG. 9 is a bottom plan view thereof;
FIG. 10 is a front elevational view thereof;
FIG. 11 is a rear elevational view thereof;
FIG. 12 is a top front perspective view thereof;
FIG. 13 is a right side elevational view of a third embodiment; the left side elevational view being a mirror image thereof;
FIG. 14 is a top plan view thereof;
FIG. 15 is a bottom plan view thereof;
FIG. 16 is a front elevational view thereof;
FIG. 17 is a rear elevational view thereof; and,
FIG. 18 is a top front perspective view thereof.
The dotted line showings in the drawings of the enclosures are for environmental purposes and form no part of the claimed design.
